INVENTOR.

FREDERICK M. VENZIE,

BY

William J. Jackson
ATTORNEY

UNITED STATES PATENT OFFICE

FREDERICK M. VENZIE, OF PHILADELPHIA, PENNSYLVANIA

BUILDING STRUCTURE

Application filed February 18, 1929. Serial No. 340,863.

This invention relates to a building construction and particularly to a ceiling composed of a precast slab of plastic material.

The invention has for one object to provide a precast ceiling slab which is constructed to be suspended from the metal floor frame of the building, which can be placed in position in a minimum time, which cooperates with adjacent slabs to form a flush ceiling, which 10 efficiently protects the metal floor frame from fire below the same, and which provides for a plastic key for the plaster coat applied to its under surface.

A further object of the present invention is 15 to provide a pre-cast ceiling slab having a cut-away portion for resting upon a hanger and having its opposite end cut away at intervals with anchors projected from the slab into said cut away portions so that clips may 20 be positioned over a channel iron and hooked to said anchors for suspension of the slab without in any way being suspended from the slab reinforcing rods.

A still further object is to provide at one 25 end of a pre-cast slab and embedded therein, angularly formed reinforcing members having hook-like portions projected into a cut away portion of the slab, whereby the hook-like portions of adjacent slabs may be se- 30 cured together by means of tie-wires.

A still further object of the present invention is to provide for an I-beam, a pair of sheet metal clips which are positioned upon the lower rail of the beam so as to receive the 35 ends of channel irons from which channel irons the slabs of the invention are suspended.

Other and further objects not at this time appearing will be described hereinafter.

The invention consists of the novel construction hereinafter described and finally claimed.

The nature, characteristic features and scope of the invention will be more fully understood from the following description taken 45 in connection with the accompanying drawings forming part hereof, and in which:

Fig. 1, is a top or plan view of several slabs constructed in accordance with the invention but omitting the I-beams and channel irons 50 from which they are suspended.

Fig. 2, is a view taken approximately upon the line 2—2 of Fig. 1, but showing parts from which the slabs are suspended.

Fig. 3, is a view in section taken upon the line 3—3 of Fig. 2.

Fig. 4, is a view in perspective of one of the reinforcing members shown at the right hand side of Figs. 1 and 2.

Fig. 5, is a similar view of one of the anchors shown at the left hand side of Figs. 1 and 2.

Fig. 6, is a similar view of one of the hangers shown in Fig. 3.

Fig. 7, is a similar view of one of the clips shown in Fig. 3.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings, the floor frame comprises I-beams 1, see Fig. 3, channel irons 2 and inverted T-shaped angle irons 3 each having a strap 4 bolted thereto as at 5. The channel irons 2 are supported by the I-beams, see Fig. 3. The lower ledges of the I-beam each have mounted thereon a clip 6, see Figs. 3 and 7, a description of which will now be given, particular reference being had to Fig. 7. The clip 6 is stamped from a single piece of sheet metal and comprises a pair of vertical strips 8 cut away at 9 central thereof. The strips at their bottoms are bent first outwardly at 10, then downwardly at 11, and thence inwardly at 12 to form a U-shaped socket for engaging over the lower ledge of an I-beam, 1, see Fig. 3. The upper parts of the strips 8 terminate in tabs 13 bent over in horizontal fashion. The ends of the channel irons 2 are fitted between the tabs 13 and the parts 10 of the clips 6, see Fig. 3.

A description will now be given of the pre-cast slabs after which the manner of their

suspension will be described. The ceiling slabs of suitable plastic material are designated 14 and as each is a duplicate of another, a description of one will suffice. At 5 one end of a slab 14 there is provided a laterally extended flange 15 having a cut away portion 16 extended therebeneath. Embedded in the slab 1 is the reinforcing member shown in Fig. 4. It comprises a one-piece 10 wire structure having a lateral portion 17 which extends along the major part of the flange 15. Extended at right angles to the part 17 is a pair of short sections 18 depending from each of which at an acute angle is 15 a section 19 from each of which sections extends a bottom section 20 which parallel the sections 18. The sections 20 each terminates in a hook-like end 21 which projects into the cut away part 16 of a slab 1, see Fig. 2. 20 The opposite end of a slab is provided with a pair of spaced, cut away portions 22, see Fig. 1. Embedded in a slab 1 are a pair of anchors having hook-like parts projected into said cut away portions 22. In Fig. 5 there 25 is shown one of these anchors which comprises a wire structure having a section 23 with other sections 24 formed at right angles thereto, each section 24 terminating in a foot 25. 30 A description will now be given of the manner of positioning the slabs 1 to the channel irons 2. Referring first to the left hand side of Fig. 2, and to Fig. 3, each slab 1 is supported at adjacent ends by means of clips, 35 best seen in Fig. 6. Each clip comprises a single piece of wire bent in the following: A horizontal bar 26 is bent upwardly to provide vertical portions 27 which are bent over in a horizontal manner to provide top bars 28 which extend at right angles to the lower bar 26. The top bars 28 in turn are bent 40 downwardly to form vertical portions 29 which parallel the vertical portions 27 and terminate in horizontal hooks 30. In positioning for example three slabs the clip just described is fitted over a channel iron 2 with the top bar 28 seated upon the top of the channel iron. The parts 23 of one of the 45 slabs are then fitted over the hooks 30 of the clip and the hooks 25 of the adjacent slab fitted over the bottom bar 26 of the clip. This arrangement is best seen in Fig. 2. Referring now to the right hand side of Fig. 2 the opposed ends of the slabs 1 which are 50 flanged are positioned by placing the flanges 15 upon the ribs of the beam 3 and securing together the hook ends 21 of the wire member shown in Fig. 4 by means of tie-wires 31. The space between the ends of adjacent slabs 55 is then filled with cementitious material 32. By the above arrangement, construction, and combination of parts I am enabled to suspend the slabs 1 from I-beams, channel irons and other metal ceiling supporting structures 60 without in any way using for the purpose the

conventional reinforcing rods 33, which is important since by the employment of independent devices for suspension purposes undue stress and strain is not imparted to the conventional reinforcing rods and they are left to perform their individual function of slab reinforcement, the advantage of which is obvious.

What I claim is:

1. In a pre-cast slab having at one end a laterally extended flange for resting upon a beam, said slab having a cut-away portion co-extensive with said flange and having at its other end a pair of spaced, longitudinally extended metal suspension members anchored in said slab at an inclination to the upper surface of the slab and having their outer ends projected into cut-away portions of the slab for beam attachment, and spaced conventional reinforcing rods extended longitudinally through said slab and independent of the suspension flange and suspension members. 70
2. A pre-cast slab having at one end a laterally extended flange for resting upon a beam, an angular member anchored in said slab, the lateral part of which reinforces said flange and longitudinal parts of which extend beyond said slab in the form of hooks, said slab having a cut-away portion co-extensive with said flange and having at its other end a pair of spaced, longitudinally extended metal suspension members anchored in said slab at an inclination to the upper surface of the slab and having their outer ends projected into cut-away portions of the slab for beam attachment, and spaced conventional reinforcing rods extended longitudinally through said slab and independent of the suspension flange and suspension members. 80
3. In combination a slab structure as described in claim 2 characterized by an I-beam and a clip, which clip has hooked relation with the inclined, anchored, suspension members of adjacent slabs. 85
4. In combination a slab structure as described in claim 2 characterized by an inverted T-shaped beam upon which the flanged portions of adjacent slabs are sustained, and a tie-wire connecting adjacent hooks of said angular members. 90
5. In combination a slab structure as described in claim 2, characterized by a channel iron and an inverted T-beam, a clip suspended from said channel iron, which clip has hooked relation with the inclined, anchored suspension members of adjacent slabs, the flange of said slab resting upon said inverted T-shaped beam. 100

FREDERICK M. VENZIE.
